BACKREST SUPPORT

Frank R. Torrey, 9805 Dallas Ave.,
Silver Spring, Md. 20901

Filed Feb. 19, 1971, Ser. No. 117,204

Term of patent 14 years

Int. Cl. D6—02

U.S. Cl. D6—200

FIG. 1

FIG. 3

FIG. 1 is a perspective view of a backrest support, showing my new design;

FIG. 2 is a left side elevational view thereof, the right side being a mirror image thereof, and

FIG. 3 is a rear elevational view thereof.

I claim:

The ornamental design for a backrest support, as shown and described.
